DEMOUNTABLE BULLDOZER ATTACHMENT

Carl D. Forte, San Diego, Calif.

Application July 5, 1941, Serial No. 401,137

4 Claims. (Cl. 262—8)

My invention relates to demountable bulldozer attachments, and its objects are to provide a means of increasing the efficiency of bulldozers through the non-slipable attachment to the moldboard thereof of readily removable earth moving equipment; to bring about a better anchorage of parts and avoidance of displacement thereof under the strain of conditions ordinarily encountered in ground moving work, as well as in unusually heavy work where additional strain is encountered. These and various other important objects and advantages will become apparent as shown in the drawings and as hereinafter set forth and described.

In the bulldozers now in general use throughout the country there is, so far as I am aware no practicable means for positively anchoring to mold boards thereof, detachable devices employed to break up the ground known as "rooters." These devices employ heavy teeth that are used to tear up heavy material such as decomposed shale and granite, tough clay, and the like, which might otherwise have to be blasted or broken up with an air hammer. In those cases where unusually hard ground is encountered, it frequently is the practice for the rooter to use but one tooth, so as to concentrate all effort thereon.

In my improved device, however, these disadvantages have been eliminated, and through the use of my demountable attachment I am able to employ the same apparatus either as a bulldozer or as a rooter, or to obtain a combined effect common to both. So far as I know, I am the first person in the art to devise a demountable attachment for a bulldozer whereby rooter teeth could be temporarily anchored thereto and practicably used where such teeth could be made effective, or whereby in place of such teeth, there could be temporarily installed and used spreader boxes, scarifiers, pipe carriers, or other articles adaptable for use with bulldozers. I have also discovered that in order to make such attachment devices effective, it is not only necessary to make the same demountable, but also to provide satisfactory means firmly to anchor the same against the possibility of displacement by reason of the very rough usage to which it is necessarily subjected. My invention will be found of particular advantage, when used with a rooter attachment, to root up pavement or ground which the teeth of an ordinary rooter cannot penetrate; the weight of the bulldozer bearing down upon such attachment causing greater penetration and consequently accomplishing more effective work. Also with such attachment, a bulldozer could for the same reason be employed with precision for ripping up shoulders on highways, where ordinary rooters could not be used; and it could be used to open up the road in advance of such rooters where it is impossible for the tractors

pulling the same to travel. My invention also will be found particularly useful in such work as in rooting circular roads, toes of slopes, gutter lines, ditches, square corners for excavations for buildings, vertical slopes for underground structures, and other work where the ordinary type of rooter is impossible of use. Such work is facilitated by the fact that one or more of my improved attachments can be secured to the bulldozer in such positions as may be found desirable, that is, at or near the right or left side thereof, or to any place thereinbetween.

Attention is hereby directed to the drawings, illustrating a preferred form of my invention, in which similar numerals of designation refer to similar parts throughout the several views, and in which,

Fig. 1 is a side elevation of my demountable attachment, showing the same secured to the main structure of the bulldozer, some of the parts being shown broken away for the purpose of better illustration;

Fig. 2 is a view of a modification of the top bar of the bulldozer, and adjacent parts, the said bar being shown in section;

Fig. 3 is a section on line 3—3 of Fig. 1 looking in the direction of the arrows;

Fig. 4 is a front elevation of the view shown in Fig. 1, and

Fig. 5 is a view in perspective of the double jaw construction of the top portion of my demountable attachment, showing it as secured to the top bar of the bulldozer and adjacent parts.

Referring to the drawings, the bulldozer 6 there shown is of the usual construction and has the customary side arms 10 and brace 11 for securing the same to the front of a tractor, by which it is pushed into desired position and operated as required. The front of the moldboard 7 of said bulldozer is formed with the face 1a, to which is removably secured in the well known way the main cutting edge 8, and also to the sides of said moldboard is affixed the usual side cutting edges 9. Preferably the said moldboard 7 is a casing of metal and is formed with the extension 12, which is reinforced by the braces 13, soldered to the bottom of said casing (see Figs. 1 and 3). Engaging with said extension 12, and straddling the braces 13, are the heavy metallic fingers 43, which are welded to, or are an integral part of, the arms 42 of the saddle 38. As shown in Fig. 3, the position so taken by the fingers 43 astride the braces 13 and the simultaneous engagement of said fingers with the extension 12, effectually anchors the saddle 38 and the lower part of my attachment against either lateral or longitudinal displacement; the braces 13 preventing sideways movement of the lower end of my attachment and the extension 12 pre-

venting any forward or backward movement thereof.

Integral with said saddle 38, or firmly attached thereto, is the large rectangular plate 39, to which are welded the corner braces 40 (triangular in cross section), which braces are also welded to the adjacent wall of the housing 44; the interior recess 45 of which is shaped to receive the shank 37 of rooter tooth 31, removably fastened in said recess by pin 35 engaging with an opening in said shank and one of the openings 32, 33 or 34 in the walls of said housing. These openings are for the purpose of elongated adjustment of said rooter tooth 31, and as is obvious, more of such openings could be provided and further adjustment of said tooth (either as retracted or extended) secured thereby. A cotter key 36 serves removably to secure said pin 35 in place as shown in the drawings. Extending downwardly on opposite sides of housing 44 are the side strips 15 and 15a, embracing the socket member 45, and secured thereto by the pin 28, passing through openings provided therefor and removably fastened therein by the cotter key 29. An overlapping collar 30, welded to said strips and to the adjacent wall of said housing, serves to hold said parts firmly in position. Within said member 45, is formed the lower socket 17, registering with the recess 46, and the upper socket 16 shaped to receive the shank 19 of the securing member 18.

Preferably, the said securing member 18 is constructed with two locker arms 21 and 22, forming a double hook; the catches 25 and 26 of which are shaped to engage with the top bar 27 of the moldboard. Being widely spaced apart as shown, the said catches firmly hold the head 20 of securing member 18 against lateral or twisting movements and thereby control the direction of application of the rooter tooth to a degree not before experienced with the commercial form of rooter now in common use. Space strips 24 may be used to increase the width of space between the catches, and a tie strip 23 may be added to give greater rigidity to the construction. As shown in Fig. 5, the double hook member 18 is not only affixed to the top bar 27 of the moldboard by the jaws of the locker arms 21 and 22, (and the top of my attachment thereby secured against any forward or backward movement thereof), but such member 18 and the top of my attachment is also anchored against lateral movement by reason of the straddling of said arms over the brace 11.

In affixing my demountable bulldozer attachment, I first remove the securing member 18 therefrom by releasing the cotter key 29, and taking out pin 28. I then place the said member in operative position by engaging the catches 25 and 26 with the top bar of the moldboard as shown in Fig. 5. Thereupon, the rooter tooth 31 having been adjusted in the desired longitudinal position through use of the pin 35 and cotter key 36, I engage the fingers 43 with the extension 12, and swing the body of the attachment upwardly so as to engage the shank 19 of member 18 with socket 16, and secure the same therein by means of pin 28 and cotter key 29, and thereby anchor the entire attachment securely in place; the result being that the rooter attachment is firmly anchored and locked from displacement in any

direction and is as rigid as if made integral with the mold board of the bulldozer, while at the same time it is readily removable therefrom. For, if it is desired to demount the attachment, the shank of the rooter tooth has only to be forced into the ground, through a slight advance of the bulldozer, when if the pin 28 is removed, the bulldozer may be backed away leaving the said tooth remaining in the ground.

10 My invention may be embodied in other specific forms without departing from the spirit or essential characteristics thereof. The present embodiment, as hereinbefore set forth, is therefore to be considered in all respects as illustrative and not restrictive; the scope of my invention being indicated by the appended claims rather than by the foregoing description, and all changes which come within the meaning and range of equivalency of the claims are therefore intended to be embraced therein.

What I claim and desire to secure by Letters Patent is:

1. In bulldozing apparatus, the combination of a frame embodying top and bottom braces therein, a moldboard incorporating a top bar and mounted upon said frame, a rooter attachment, detachable double hook means for securing and anchoring the top part of said attachment to the top of said moldboard, and to one of said top braces, and detachable saddle means for securing and anchoring the bottom part of said attachment to the bottom of said moldboard and to one of said bottom braces.

2. In bulldozing apparatus, the combination of a frame, a top bar, top and bottom braces incorporated in said frame, a moldboard mounted upon said frame and located below said top bar, a rooter attachment, detachable double hook means securing and anchoring the upper part of said attachment to the said top bar and astride one of top braces, detachable means securing and anchoring the bottom part of said attachment to the bottom of said moldboard and astride one of said bottom braces, and means for locking said attachment against movement in any direction after it has been so anchored and secured.

3. In bulldozing apparatus, the combination of a moldboard, top and bottom braces affixed thereto, an extensible rooter attachment, detachable means securing and anchoring the upper part of said attachment directly to the said moldboard and to one of the top braces, detachable means securing and anchoring the bottom part of said attachment directly to the bottom of said moldboard and to one of said bottom braces, and means for locking said attachment against movement in any direction after it has been so anchored and secured.

4. In bulldozing apparatus, the combination of a moldboard, top and bottom braces secured thereto, an extensible rooter attachment, detachable double hook means securing and anchoring the upper part of said attachment directly to the top of said moldboard and astride one of the top braces, detachable means securing and anchoring the bottom part of said attachment directly to the bottom of said moldboard and astride one of said bottom braces, and means for locking said attachment against movement in any direction after it has been so anchored and secured.

CARL D. FORTE.
